CLAIM

The ornamental design for an intelligent remote control, as shown and described.

DESCRIPTION

FIG. 1 is a top perspective view of an intelligent remote control showing our new design;

FIG. 2 is a bottom perspective view thereof;

FIG. 3 is a front elevational view thereof;

FIG. 4 is a rear elevational view thereof;

FIG. 5 is a right side view thereof, the left side view being a mirror image thereof;

FIG. 6 is a top plan view thereof; and,

FIG. 7 is a bottom plan view thereof.

The broken lines are for the purpose of illustrating portions of the intelligent remote control which form no part of the claimed design.
